ROTARY PRINTER FOR CONVEYED ARTICLES
James F. Mellison, Tacoma, Wash., assignor to Weyerhaeuser Company, Tacoma, Wash., a corporation of Washington

Filed Aug. 8, 1962, Ser. No. 215,554

1 Claim. (Cl. 101—35)

The present invention relates to a rotary marking apparatus, and specifically relates to a high-speed rotary marking apparatus which is capable of continuously and clearly marking an object which is conveyed past it at varying high speeds.

It is desirable to mark products so that a customer or consumer will be assured that the material which he is purchasing, or the product made from such material, is of the quality and of the manufacture which he has specified. For most products a single mark will suffice. However, a single mark will not afford protection on products, such as lumber, which can be altered easily after manufacture.

It is customary to place a mark on the ends of boards. However, these marks may be removed by cutting the end from the board when cutting the board to length, or may be hidden by butting the end of the board against and adjacent board in a construction. The ultimate consumer then has no assurance that he is purchasing the product that he has ordered, or that the product is of the quality that he has specified.

It is, therefore, necessary to provide a mark that cannot be removed readily from the board and that cannot be hidden during construction. This mark must appear continuously along the entire length of the board, either on the side edge or on the rear face or on an overlapped section of the front face, and allows the article to be cut to any length and to be placed in a construction and still be identifiable. To be economical, the mark must be applied during the normal course of manufacture and during the last stages of manufacture. These requirements would be fulfilled by applying the mark during a conveying operation and after the last finishing operation.

The speed of the lumber during the conveying and finishing operations may vary from 300 feet to 900 feet a minute, and any marking instrument must, therefore, be responsive readily to these speed variations in order to avoid blurring of the mark on the board. The mark must be clear and distinct if it is to be meaningful.

Therefore, it is an object of this invention to provide an apparatus that will mark lumber automatically and at varying high speeds.

It is also an object of this invention to provide a rotary marking apparatus that will print evenly and distinctly, without slippage, at varying high speeds.

These and other objects of this invention will become readily apparent upon a reading of the following specification in conjunction with the attached drawings.

FIGURE 1 is a top plan view of a preferred form of the marking apparatus.

FIGURE 2 is a side elevational view of the marking apparatus shown in FIGURE 1.

FIGURE 3 is a cross-sectional view taken along lines 3—3 of FIGURE 1, showing the inking reservoir and the inking roller.

Although the marking apparatus has been illustrated as edge marking a board, it will be readily understood that other products may be similarly edge-marked. It will also be understood that a change in the placement of the ink reservoir will allow the apparatus to mark the face of the material.

All of the operating elements of the marking apparatus depend from, or are mounted above, a pivoted mounting plate 10. The three ink rollers—marking roller 11 which

is rotated frictionally or driven by the passing article and which places the mark on the passing article, ink spreading roller 12 which is rotated frictionally or driven by marking roller 11 and which places an even amount of ink on the marking roller 11, and the ink supply roller 13 which is rotated frictionally or driven by ink spreading roller 12 and which supplies ink to roller 12—depend from plate 10, and the ink reservoir 14 is mounted above plate 10.

The reservoir 14 holds a quantity of ink 15, and supplies this ink to the ink rollers at a steady rate, and, in its preferred form, has an annular chamber 16 in which the ink 15 is stored. The chamber 16 is formed by an upper wall 17, a lower wall 18, and a pair of concentric cylindrical side walls—outer cylindrical wall 19 and inner cylindrical wall 20. The inner and outer cylindrical walls 19 and 20 are joined to the upper and lower walls 17 and 18 in any convenient manner, and, as illustrated, the inner cylindrical wall 20 may be formed integrally with one of the upper or lower walls 17 or 18. The outer cylindrical wall 19 is formed preferably of a transparent or translucent material which will allow the height of ink in the chamber 16 to be noted so that the chamber may be refilled with ink as needed.

The ink is placed into the annular reservoir chamber 16 through the filling hole 21 in the upper wall 19 of the reservoir. The filling hole 21 has a cap 22 which prevents dust and other foreign material from entering the reservoir chamber 16 and eventually clogging the ink distribution system of the marking apparatus. The ink exits from the annular chamber 16 through a series of radial outlet passages 23 which extend through the inner cylindrical side wall 20 and the lower wall 18, and connect the annular chamber 16 with the central passage 24 of the reservoir 14. The passages 23 extend from the juncture of the inner cylindrical side wall 20 with the lower wall 18 radially downwardly to the central passage 24, allowing the ink to flow by gravity from the annular chamber 16 into the central passage 24.

The central passage 24 of the reservoir 14 is formed by the threaded passage 25 in the upper wall 17, the inner passage 26 formed by the inner cylindrical side wall 20, and the passage 27 in the lower wall 18. The three passages 25, 26, and 27 are aligned, and, in the preferred construction, are located centrally of the reservoir. The lower passage 27 is closed by a needle valve 28. The needle valve, which is threadably mounted in the upper threaded passage 25, has a handle 29 which may be turned in a clockwise or counterclockwise direction to lower or raise the needle valve 28 within the passage 24. This action stops or adjusts the flow of ink through the lower passage 27 and meters the quantity of ink being transported to the ink rollers.

The ink flows from the lower passage 27 into a passage 30 which is aligned with the passage 27. Preferably, passage 30 extends centrally of a lower threaded extension 31 on the reservoir 14. The extension 31 is attached in any manner to the lower wall 18, and may, as shown, be formed integrally with the lower wall 18. The threaded extension 31 allows the reservoir 14 to be removably mounted in the threaded hole 32 of an L-shaped bracket 33 that is welded or otherwise fixed to plate 10. This mounting allows the reservoir 14 to be spaced above plate 10 and to be fixed with respect to plate 10, and allows the central passage 24 of the reservoir 14 and the outlet passage 30 to be aligned with the ink supply roller 13 and its shaft 34.

From the outlet passage 30 of the reservoir extension 31, the ink flows into the central passage 35 of the hollow rotatable shaft 34. The ink is retained within the passages 30 and 35 at their juncture by providing a cupped outer end 36 on shaft 34 and shaping the outer end 37 of the

threaded extension 31 to conform to the shape of the cupped end 36. This shape will allow end 36 of the shaft to be spaced slightly from the end 37 of the extension so that the shaft 34 may rotate easily. Otherwise, a bearing material or a friction reducing coating must be provided on the ends 36 and 37.

The shaft 34 is rotatably mounted in a bearing assembly 38 having an outer cylindrical housing 39 which is welded or otherwise fixed in mounting plate 10. The housing 39 has inner annular grooves 40 and 41 formed in its upper and lower ends. A ball bearing assembly 42 fits frictionally within each of the annular grooves 40 and 41, and each assembly 42 is held within the grooves by a pair of opposed segmental plates 43 which are fastened to the ends of housing 39. Screws, such as screws 44, may be used for fastening these plates. The segmental plates 43 are preferably arcuate, having an outer edge that conforms to the shape of the outer edge of housing 39 and an inner edge that conforms to the shape of the inner edge of the outer fixed ring 45 of ball bearing assembly 42, so that the plate extends only over the housing 39 and the outer fixed ring 45.

In addition to the outer fixed ring 45, each of the ball bearing assemblies 42 has an inner rotatable ring 46. The adjoining faces of the outer fixed ring 45 and the inner rotatable ring 46 are spaced from each other, and have aligned curved grooves which form a race 47 for the ball bearings 48. The inner rotatable ring 46 of the ball bearing assemblies 42 may, therefore, rotate easily with respect to the bearing housing 39 and the mounting plate 10.

The inner rotatable rings 46 frictionally hold the hollow shaft 34, allowing it and its associated ink supply roller 13 to rotate easily with respect to mounting plate 10. The ink supply roller 13 is mounted frictionally on the lower end of the hollow shaft 34 and is held in position on the shaft by a key 49 which is mounted in a keyway 50 in the shaft 34 and a keyway 51 in ink supply roller 13.

The outward force created by the rotation of the ink supply roller 13 and the hollow shaft 34 causes the ink in the central passage 35 of shaft 34 to flow outwardly through the radial passages 52 in the shaft 34 at the lower end of passage 35. The ink flows from the radial passages 52 into a grooved annular reservoir 53 on the inner periphery 54 of the ink supply roller 13 adjacent the shaft 34. The rotation of ink supply roller 13 causes the ink to flow to the outer edge of reservoir 53 and to form an even pool in the outer portion of reservoir 53. This pooling provides an even flow of ink through all of the radial passages 55, which extend through the inner cylindrical wall 56 of roller 13 and connect the annular reservoir 53 with the inner reservoir 57 of the ink supply roller 13, because each of the radial passages 55, which are located above and inwardly of the outer edge of grooved reservoir 53, receives ink from the top, or inner peripheral surface, of the pool of ink in the reservoir 53, minimizing the tendency of the ink to flow through only the passages 53 opposite the passage 52 in shaft 34.

The ink entering the inner reservoir 57 from the radial passages 55 flows along the bottom surface 58 of the reservoir 57 and tends to spread across the entire surface, again evening the flow of ink through the ink supply roller 13.

From reservoir 57, the ink flows into an outer grooved reservoir 59 formed in the inner face of the outer cylindrical wall 60 of ink supply roller 13. Preferably, the outer cylindrical wall 60 is concentric with the inner cylindrical wall 56. The outer annular reservoir 59 is shaped similarly to the inner annular reservoir 53 and performs in the same manner. Ink again forms in a pool on the outer surface of the annular reservoir 59, and ink from the top, or inner peripheral surface, of the pool flows outwardly through a number of radial passages 61 in the outer wall 60. The radial passages 61, which are located above the outer edge of annular reservoir 59, con-

nect the annular reservoir 59 with the inking felt 62 which is mounted on the outer peripheral face 63 of the ink supply roller 13.

With many types of ink and under many speed conditions, it is unnecessary to have such a complete reservoir system and a series of radial tubes extending between the inner peripheral face 54 of the ink supply roller 13 and the outer peripheral face 63 of the ink supply roller 13, or a passageway formed by a pair of plates mounted internally of the ink supply roller 13 is adequate. This latter system works exceptionally well when the ink is introduced to the inking felt 62 under a slight pressure. In any system used the flow of ink to the inking felt 62, a bearing or washer felt, is regulated so that the entire felt is filled with ink by the wicking action of the felt, but the felt is not oversaturated since this condition would cause ink to be thrown from the revolving roller 13.

The ink felt 62 is held on the outer peripheral face 63 of the ink supply roller 13 and is aligned with the upper and lower faces of the ink supply roller 13 by upper and lower plates 64 and 65, mounted upon the upper and lower faces of the ink supply roller 13. The outer periphery of each of the plates 64 and 65 is spaced slightly inwardly of the outer periphery of the inking felt 62 so that these plates do not come in contact with ink spreading roller 12 as the inking felt 62 transfers the ink to the outer surface of the ink spreading roller 12.

The outer surface of the ink spreading roller 12 and the outer surface of the marking roller 11 are of rubber or some other material of a type normally found in printing wheels. This material is impervious to the solvents used in the ink and its choice, therefore, will depend in part upon the ink used and the solvent used for that ink.

Both the ink spreading roller 12 and the marking roller 11 have upwardly extending shafts—shaft 66 on ink transfer roller 12 and shaft 67 on the marking roller 11—that extend through bearing assemblies which are similar in construction to the bearing assembly 38 described above. The bearing assembly 68 of marking roller 11 is fixedly mounted in plate 10, and the bearing assembly 69 of ink transfer roller 12 is resiliently mounted on plate 10 by means of a slidably mounted or movable plate 70.

The movable plate 70 is mounted over an aperture 71 in plate 10 through which bearing assembly 69 and shaft 66 extend. The path of travel of plate 70 is fixed by a number of elongated guide slots 72 in the plate and by a number of bolts 73 which extend through apertures in plate 10 and through the guide slots 72. The ink spreading roller 12 depending from plate 70 is biased inwardly against the ink supply roller 13 and the marking roller 11 by a tension spring 74 that extends between a pin 75 fixed to plate 70 and a pin 76 mounted on plate 10. One of the mounting pins 75 or 76 is adjustable so that the tension on spring 74 may be adjusted, varying the pressure between the rollers as variations in the ink consistency and in operating conditions require.

As illustrated, the mounting pin 76 on plate 10 may be adjustably positioned with respect to plate 10. The adjustability is provided by an elongate threaded shaft 77 extending at right angles to the pin 76 and extending through a fixed bracket 78 on the mounting plate 10. A pair of nuts 79 and 80 are mounted on the shaft 77, one on each side of the bracket 78, and the clockwise or counterclockwise rotation of these nuts moves the pin 76 toward or away from the bracket 78, adjusting the position of the pin 76 with respect to the plate 10 and varying the pressure on ink spreading roller 12.

The ink picked up by ink spreading roller 12 from ink supply roller 13 is transferred to the raised symbols 81 of a printing roll 82 on the outer periphery of marking roller 11. Printing roll 82, forming the outer surface of marking roller 11, is fixed both vertically and circumferentially with respect to marking roller 11 so that there will be no vertical or circumferential slippage between the printing roll 82 and the marking roller 11. One method of ob-

taining this arrangement is through the use of a peripheral groove in the outer face of marking roller 11 into which an inner peripheral tongue on printing roll 82 fits and locks.

The ink on the raised symbols 81 is transferred to the board 83 carried by the marking roller 11 by the conveyor 98, causing a continuous series of symbols to appear along the length of the board 83. The symbols on the board 83 are not blurred because the peripheral speed of the marking roller 11, which is rotated frictionally or driven by the board 83, is the same as the speed of the board. Therefore, it is necessary that the marking roller 11 be held against board 83 with enough pressure to cause it to be moved frictionally by the board without slippage and to react instantaneously to any changes in the speed of the board. This pressure is obtained by a tension spring 84 which extends between a pin 85 fixedly mounted upon the conveyor frame 86 or on some other object which has a fixed reference with respect to the path of travel of the board 83, and a pin 87 which is mounted on plate 10. One of the pins is adjustable to vary the tension on spring 84.

Again, the pin on plate 10, pin 87 is illustrated as being adjustable. Its construction and operation is identical to that of adjustable pin 76, and it has an elongate threaded shaft 88 extending at right angles to the pin 87 and extending through a fixed bracket 89 mounted on plate 10. Again, a pair of nuts 90 and 91 adjust the placement of pin 87 with respect to the bracket 89 and mounting plate 10.

The tension spring 84 rotates the mounting plate 10 and its dependent inking rollers 11, 12, and 13, inwardly around a pivot shaft 92 toward the fixed pin 87 and the board 83. The lower end of the pivot shaft 92 threadably engages a bushing 93 which is mounted in the conveyor frame 86 adjacent the pin 85 and a clockwise or a counterclockwise revolution of the shaft 92 allows it to be raised or lowered with respect to the frame 86.

This raising or lowering of the pivot shaft 92 also raises or lowers the mounting plate 10 and its associated ink rollers because the mounting plate 10, which is rotatably mounted onto the pivot shaft 92 by a bushing or bearing 94, has a fixed longitudinal position with respect to the pivot shaft 92. This allows the marking apparatus and the symbols to be positioned with respect to the side face or the top face of the board 83 by positioning the shaft 92.

When no board 83 is present on the conveyor, the spring 84 will rotate the marking apparatus and the marking roller 11 into the path of an oncoming board. To limit this inward travel, an adjustable stop is provided. This stop comprises a bolt or machine screw 95 that is threadably mounted through the pin 85 on the conveyor frame 86 and which contacts an upright plate 96 on the mounting plate 10. This stop may be adjusted for various sizes of boards and will stop the rotation of the marking apparatus slightly inwardly of its marking position.

As may be seen, the apparatus, which is driven by the passing article, should be capable of stopping and starting quickly and of changing speeds quickly and, therefore, should be as inertialess as possible and as easily rotatable as possible. The preferred material of construction is aluminum or magnesium, and the preferred wheel diameter for peripheral speeds up to 900 feet a minute is approximately 6 inches. Smaller diameters may be used for lesser speeds, although there is a tendency for the smaller diametered rollers to throw ink at the higher speeds.

The rollers may mark the upper or lower sides of passing boards by placing the mounting plate in a vertical position instead of the horizontal position illustrated. The only change required is the placement of the ink

reservoir 14 with its axis parallel to mounting plate 10 instead of normal to the mounting plate as shown.

Although the specific details of a preferred embodiment have been set forth above, it will be apparent that many changes and modifications may be made herein without departing from the spirit of the invention. It will therefore be understood that what has been described herein is intended to be illustrative only, and is not intended to limit the scope of the invention. What is claimed is:

I claim:

A marking apparatus for marking objects traveling in a path therewith comprising
 a pivot shaft having a fixed spaced relationship with said path of travel;
 a frame pivotably mounted on said shaft, said frame having an aperture;
 an ink marking roller;
 a shaft for said ink marking roller, said shaft being rotatably mounted on said frame;
 an ink supply roller,
 a shaft for said ink supply roller, said shaft being rotatably mounted on said frame;
 said marking roller and said supply roller being aligned with each other and spaced apart from each other on opposite sides of said aperture;
 an ink spreading roller,
 said ink spreading roller being aligned with said ink marking roller and said ink supply roller;
 a shaft for said ink spreading roller, said shaft extending through said aperture and being rotatably mounted on a plate,
 said plate being mounted over said aperture and being slidably mounted on said frame, said plate being slidably in a path that carries said spreading roller into tangential contact with both said ink marking roller and said ink supply roller whereby ink may be transferred from said ink supply roller to said ink spreading roller and from said ink spreading roller to said ink marking roller,
 a first mounting member on said plate,
 a second mounting member on said frame,
 a spring extending between said first and second mounting members and biasing said spreading roller into tangential contact with both said marking roller and said supply roller;
 a third mounting member on said frame,
 a fourth mounting member having a fixed spaced relationship with said path of travel,
 a spring extending between said last two mentioned mounting members and biasing said frame toward said path of travel of said object and said marking roller into said path of travel of said object;
 an abutment on said frame,
 a stop member having a fixed space relationship with said path of travel, said stop member being aligned with said abutment so that said marking roller will move only a fixed distance into the path of travel of said object.
